UNITED STATES PATENT OFFICE.

LENSON JOHNSON, OF CHICAGO, ILLINOIS.

KNIFE AND PENCIL SHARPENER.

SPECIFICATION forming part of Letters Patent No. 707,118, dated August 19, 1902.

Application filed December 18, 1901. Serial No. 86,391. (No model.)

To all whom it may concern:

Be it known that I, LENSON JOHNSON, a citizen of the United States, residing at Chicago, in the county of Cook and State of Illinois, 5 have invented a new and useful Knife and Pencil Sharpener, of which the following is a specification.

My invention relates to combined tools for grinding knives, sharpening pencils, and other 10 similar purposes; and my object is to provide an inexpensive and very desirable device adapted to the use of draftsmen, writers, bookkeepers, or others who use knife erasers and whose pencils on account of continued 15 use require frequent sharpening, the same being fully described hereinafter and illustrated in the accompanying drawings, in which—

Figures 1 and 2 are respectively front and 20 rear elevations of a machine in which is embodied my improvements. Fig. 3 is a side elevation looking into the large end of the pencil-holder. Fig. 4 shows, respectively, a side and a front elevation of the top portion of the 25 supporting-post to plainly illustrate the screw-threaded part of a journal-box in which the grinding-wheel shaft is mounted. Fig. 5 shows, respectively, a rear and a side elevation of the pencil-holder, whose boss is internally 30 screw-threaded to register with the screw-threads on the outside of the journal-box shown in Fig. 4.

Similar numerals indicate like parts throughout the several views.

The post 1 is provided with a broad base-flange to receive screws for securing the machine firmly in position on a disk or table. At one side of post 1 projects a pin, upon which is revolvably mounted the internal crank 40 gear-wheel 2, which has a crank-pin 3. There is a horizontally-disposed journal-box 4 at the top of post 1, in which box is mounted shaft 5, and at one end of the latter is secured a small pinion 6, which gears with cog-wheel 2, 45 as shown in Fig. 1. At the opposite end of shaft 5 from pinion 6 are flanges between which are secured a grindstone 7 and a rotary cutter 8, the grindstone serving to sharpen small tools, while the rotary cutter is adapted 50 to sharpen pencils, which are held in position to insure the proper taper by being inserted into the conical holder 9.

The pencil-holder is provided with a boss 10, which is interiorly screw-threaded, as before stated, and is split at one side, the adjacent split portions being held together by a binding-screw 11 to clamp the holder on the screw-threaded portion 12 of journal-box 4, so that the holder by being revolved on the box may be quickly adjusted to the proper 55 position relative to the rotary cutter, so that the pencil may be dressed to either a blunt or sharp point, as may be necessary. The pencil-holder may be clamped in position to easily turn upon the journal-box, so that the 60 pencil serving as a lever may be used to turn the holder to any position from that shown or may be firmly clamped in position should but one size of point be desired. On account 65 of the pencil-holder being cut away tangentially at one side 13 into the tapering hole thereof one side of the pencil when inserted in the holder projects outwardly within reach of the revolving teeth of the rotary cutter, when it is obvious that if the pencil is slowly 70 revolved by the fingers it will be cut to the desired conical form. The screw-threads on the journal-box always prevent the holder, when not being revolved, from any movement either to or from the rotary cutter, so that with 75 any given relative position of the holder the same size of point may be always produced.

I claim as my invention—

1. A combined knife and pencil sharpener, 80 consisting of a journal-box, a revoluble shaft, a rotary cutter and a grindstone mounted on the shaft which latter is mounted in the journal-box, a hollow pencil-holder, a longitudinal opening into the hollow portion of said holder, a boss attached to said holder and the 85 said boss attached to the journal-box, and so disposed that the longitudinal opening in the pencil-holder is close to the rotary cutter, substantially as and for the purpose stated.

2. A combined knife and pencil sharpener 90 consisting of a journal-box having a portion thereof exteriorly screw-threaded, a revoluble shaft, a rotary cutter and a grindstone, the cutter and grindstone mounted on the shaft and the latter mounted in the journal-box, a hollow pencil-holder, a longitudinal opening into one side of said holder and exposing the hollow portion thereof, a hollow 95 boss interiorly screw-threaded and attached

to the holder, said boss mounted on the screw-threaded portion of the journal-box with the longitudinal opening in the holder close to the rotary cutter, and means for revolving the shaft, substantially as stated.

3. In a combined knife and pencil sharpener, a supporting-post having a journal-box mounted thereon, a revoluble shaft mounted in the journal-box, a grindstone and a rotary cutter mounted on one end of the shaft and a pinion cog-wheel mounted on the other end thereof, a pin mounted on the supporting-post, an internal cog-wheel revolvably mounted on the pin and in engagement with

the pinion cog-wheel, a hollow pencil-holder, 15 one side of said holder having a longitudinal opening, said holder attached to the journal-box with said opening close to the rotary cutter, and means for revolving the internal cog-wheel substantially as and for the purpose 20 stated.

In testimony whereof I have signed my name to this specification in the presence of two subscribing witnesses.

LENSON JOHNSON.
